(57) **CLAIM**

Having described my invention, I claim the ornamental design for a golf ball and club cleaner, as shown and described.

DESCRIPTION

FIG. 1 is a perspective view showing the front top cover and left side of the invention.

FIG. 2 is a perspective view showing the front, right side, raised top cover and inside top of the invention.

FIG. 3 is a front view of the invention.

FIG. 4 is a right side view of the invention showing the hand crank.

FIG. 5 is a left side view.

FIG. 6 is a rear view of the invention; and,

FIG. 7 is a top plan view of the invention.

The bottom view is not shown as it is flat with no special details.
